APPARATUS FOR BREAKING BILLETS OR
LIKE MATERIALEmil C. Stolberg, Glen Ridge, N. J., assignor to
American Car and Foundry Company, New
York, N. Y., a corporation of New Jersey

Application May 2, 1941, Serial No. 391,554

7 Claims. (Cl. 29—66)

This invention relates in general to apparatus for applying tremendous pressures and in particular to such apparatus designed to break billets or other material.

In the past machines for applying tremendous pressure have been designed, thus necessitating extremely heavy machines. Very often after a machine has been purchased emergencies will arise wherein added pressure capacity is needed but in attempting to increase the pressure capacity it has been necessary to reinforce the frames of the machine and increase the power output of the prime mover. It is an object, therefore, of the present invention to provide an apparatus which can be readily attached to existing machines and increase their capacity many fold without in any way stressing the frame or the prime mover beyond the capacities for which they were designed.

A further object of the invention is the provision of a self-contained leverage mechanism by means of which the power of a bulldozer, press or other machine may be increased.

A still further object of the invention is the provision of a leverage system for power applying machinery such as presses, bulldozers, etc., and in which the reaction forces of the leverage are absorbed within the apparatus and not transferred to the machine and frame.

Yet another object of the invention is the provision of a pressure applying tool slidably carried by the back stop and self-retractable away from the material which is being pressed or broken.

These and other objects of the invention will be apparent to persons skilled in the art from a study of the following description and accompanying drawings, in which:

Figure 1 is a side view of the machine, which in this case is a bulldozer, with part being in section and taken substantially on line 1—1 of Fig. 2;

Fig. 2 is a plan view of the apparatus with the parts shown in final closed or pressure applying position;

Fig. 3 is a sectional view taken substantially on line 3—3 of Fig. 2 and showing in particular the manner of attachment between one of the levers and the machine cross-head;

Fig. 4 is a sectional view taken substantially on line 4—4 of Fig. 2 and showing in particular the anchorage for one of the levers;

Fig. 5 is a sectional view taken substantially on line 5—5 of Fig. 2 and showing in particular the self-retractable sliding pressure applying tool carried by the back stop element;

Fig. 6 is a sectional view taken substantially on line 6—6 of Fig. 2 and showing the anchorage of the other lever on the back stop;

Fig. 7 is a sectional view taken substantially on line 7—7 of Fig. 2, while

Fig. 8 is a sectional view taken substantially on line 8—8 of Fig. 2 and disclosing the work supporting portion of the back stop.

Referring now to the drawings in detail, and in particular to Figure 1, it will be seen that the power machine here illustrated is a bulldozer and consists of a bed plate or frame 2, upon which is mounted an axle 4 driven by any suitable power applying means (not shown). The axle 10 has keyed thereto a fly-wheel 6 carrying a crank pin 8 which, through pitman or connecting rod 10, is connected to pin 12 on cross-head 14. The cross-head 14 is slideable relative to the machine frame and has its front face provided with slots 15 for reception of bolts 16 in order that suitable tools or equipment may be fastened to the cross-head. Normally, the pressure applied to the material by the cross-head is absorbed by back stop means bolted or otherwise secured to the horns 18 which are integral with the machine frame and of sufficient strength as to absorb the entire power input of the machine. Insofar as the preceding description is concerned a conventional bulldozer has been described and it will be seen that if power beyond the machine capacity were applied through the crank shaft to the cross-head, then there would be the liability of failure of the moving mechanism or of the horns.

In order to increase the power of the machine 20 without in any way stressing the frame or machinery beyond its designed limits a leverage mechanism, as clearly shown in Fig. 2 and the various sectional views, has been provided. This mechanism consists in general of a back stop portion A, levers B and pressure applying tool C. The back stop portion is of general channel form, having a back or pressure receiving portion 20 secured by bolts 22 to the horns of the machine frame. From this back portion upper and lower flanges 24 and 26, respectively, extend forwardly toward the cross-head as more clearly shown in Fig. 4 and have formed therein openings for the reception of anchor bolts or pins 28 and 30 as shown in Fig. 2. As more clearly shown 35 in Figs. 2, 6 and 8, the back portion of the back stop is formed with spaced pressure receiving portions or ribs 32 joined together by a curved portion providing clearance for the material which is to be broken as a beam supported at its ends. In order to assist passage of the extremely heavy material through the machine rollers 34 are mounted on the lower flange of the back stop member and these rollers will not only assist in transfer of the material through the machine, but will act as supports for the short material when broken.

As clearly shown in Figs. 2 and 5, the pressure applying or breaking tool C, is formed with a substantially plane back surface 36 and a projecting V-shaped nose 38. In order to receive

this breaking tool or pressure applying member portions of the upper and lower flanges 24 and 26 of the back stop member are removed and ears 40 formed on the breaking tool extend through these openings and have attached thereto bolts or other means 42. These bolts or other means extend through angular brackets 44 carried on the back stop flanges and form a seat for one end of compression spring 46, the other end of which bears against a washer held in place by a nut 48 carried on the bolt. In this manner the pressure applying or breaking tool is slidably carried by the back stop member and is retractable from the material through the action of the compression springs 46.

In order to apply pressure to the pressure applying or breaking tool a leverage system B is provided. This leverage system consists of a pair of lever arms 50 joined together at one end by a hub 52, having an opening therethrough for reception of pivot bolt or trunnion 28, previously referred to. The hub portion of these levers is clearly shown in Fig. 4. The ends of the levers 50 opposite from the hub have an opening therethrough to receive a pivot bolt 54 extending through the levers and through a connecting link 56 (Fig. 1) disposed between the spaced lever arms. The opposite end of the short connecting link 56 is adapted to be received between spaced jaws 58 and be mounted for pivotal motion on a pin 60 carried by the jaws, which in turn are bolted to the cross-head of the machine by bolts 62. The leverage system also includes a heavy lever 70 pivoted at one end on pin or trunnion 30 (Figs. 2 and 6) and extending across the apparatus between the spaced lever arms 50. The remote end of lever arm 70 has an opening therethrough to receive a pivot bolt 72 extending through spaced connecting arms 74, the inner ends of which may turn on a pivot bolt 76 extending through a tongue 78 of a member bolted to the machine cross-head by bolts 80. The spaced levers 50 and the lever 70 are formed adjacent their trunnion end with rounded noses 82 adapted to bear upon the plane back 36 of the pressure applying or breaking tool carried by the back stop element. It will be seen that application of pressure to the outer ends of the levers 50 and 70 will cause the noses 82 to move the breaking tool toward the material which is to be broken. It will also be seen that, since the distance between the respective lever trunnions and the point of contact of the levers with the breaking tool is relatively short compared with the distance between the trunnion and the point of pressure application by the cross-head, a vast increase in power is obtained. In the present instance the distance from the trunnions to the breaking tool is approximately one-third the distance from the trunnion to the point of power application.

By analyzing the forces acting, it will be seen that if a force of value F is applied by the cross-head this force is applied to the lever ends, thus each lever end will receive a force equivalent to F divided by 2 but, since the lever arms give a power multiplication of substantially 3 in the present instance, the pressure applied by the two levers to the breaking tool will be equivalent to one-half F multiplied by 2 times 3 or 3 F. Such a force would, if directly applied to the frame, break the same but, since the levers are anchored by trunnions 28 and 30 to the back stop, a portion of the force is absorbed and transferred directly through the flanges of the back stop to the

material supports. In the present instance the amount of transfer by each trunnion will be one-half F times 3 and the two trunnions will, therefore, absorb one-half times 3 times 2 or 3 F. 5 Since the force F is applied by the cross-head 14 of the machine to the levers the horns 18 can only resist an equal force F. It is apparent that by varying the lever arms and designing the back stop properly, any desired power multiplication can be obtained without in any way stressing the machine frame or cross-head which need absorb only the power for which the machine was originally designed.

As clearly shown in the various figures and 15 particularly in Fig. 2, the mechanism has been shown in the position which it assumes when the cross-head is at its full forward or pressure stroke and in which position the material M, indicated by dotted outlines in the figures, has been 20 broken and moved to the position M' (Fig. 5). It will be seen that upon retraction of the cross-head, that is, during movement of the cross-head toward the left hand side of Fig. 2, the short connecting links 56 and connecting arms 25 74 will drag the levers 50 and 70 away from the back stop and rotate the same on trunnions 28 and 30 respectively. Such rotation of the levers will move the nose 82 away from the pressure applying tool. Movement of the nose of the 30 levers away from the pressure applying tool will permit springs 46 to retract the tool until such time as it will strike the remaining portion of the upper and lower flanges of the back stop, as clearly shown in Fig. 5. With the breaking tool 35 retracted, the material M may be easily fed into the machine by moving along the supporting rollers to their proper position. Swinging of the levers 50 and 70 during movement of the cross-head away from the back stop is easily accommodated due to the pivotal connection of the levers to the cross-head by connecting links 56 and 74 which will assume an angular position. Application of driving power to the cross-head 40 after the material is in position, will cause the cross-head to move toward the position shown in Fig. 2 applying tremendous pressure to the breaking tool, with the result that the material is ruptured.

It will be readily seen that by the use of the 50 apparatus just described the capacity of existing machines may be readily increased without any danger of over-stressing the machine. In this way, under emergency conditions, where it is impossible to obtain new, heavy machinery, existing machinery may be readily converted for 55 heavy duty purpose without in any way endangering the machine. While the apparatus has been described more or less in detail with reference to one specific form thereof, it will be apparent to persons skilled in the art of pressing and breaking metal that various modifications and rearrangements of parts may be made but all such modifications and rearrangements of parts are contemplated as will fall within the 60 scope of the appended claims defining my invention.

What is claimed is:

1. As an article of manufacture for machines of the character described, a combined back stop and power multiplier comprising, a channel form back stop adapted to be secured to the machine and receive material between the flanges, levers fulcrumed at one end on the back stop by pins passing through the back stop flanges, means adapted to connect the other end of said levers

to the machine crosshead adjacent the side of the machine opposite the pin fulcruming the respective lever on the back stop, and a pressure applying tool carried by the back stop flanges and movable by an intermediate portion of said levers toward the web of the channel form back stop.

2. As an article of manufacture for machines of the character described, a combined back stop and power multiplier comprising, a channel form back stop adapted to be secured to the machine and receive material between the flanges thereof, pins extending through the flanges of the channel form back stop in spaced relation to the web thereof, crossed levers movable between said flanges and being fulcrumed at one end on said pins, link means adapted to connect the other end of said levers to the machine crosshead for movement thereby, and a pressure applying tool carried by the back stop flanges, said pressure applying tool being engageable by intermediate portions of said crossed levers and movable thereby toward the web of the back stop.

3. As an article of manufacture for machines of the character described, a combined back stop and power multiplier comprising, a channel form back stop adapted to be secured to the machine and receive material between the flanges thereof, pins extending through the flanges of the channel form back stop in spaced relation to the web thereof, crossed levers movable between said flanges and being fulcrumed at one end on said pins, link means adapted to connect the other end of said levers to the machine crosshead for movement thereby, a pressure applying tool carried by the back stop flanges, said pressure applying tool being engageable by intermediate portions of said crossed levers and movable thereby toward the web of the back stop, and resilient means connecting said pressure applying tool and back stop flanges for constantly urging said tool away from the web of the back stop and toward the intermediate portions of said crossed levers.

4. In an apparatus of the character described, a machine frame, a back stop secured to the frame and providing supports for material to be broken, a crosshead movable toward and away from said back stop, crossed levers fulcrumed on said back stop and pivotally connected to said crosshead and movable therewith, and a breaking tool engageable by an intermediate portion of said crossed levers and movable in unison with said levers in at least one direction to apply breaking pressure on said material, said breaking tool being free of connection to said levers but being held in contact therewith by resilient means carried by the back stop.

5. In a machine for breaking billets or other materials the combination of a rigid machine frame, a crosshead movable relative to said rigid machine frame, said frame being capable of absorbing and said crosshead of delivering pressures up to a predetermined maximum without permanent deformation or rupture, and means interposed between said frame and crosshead and providing a support for billets or other materials to be broken and of developing pressures in excess of said predetermined maximum and sufficient to break the billets or other material without exceeding the predetermined maximum

5 which the machine frame and crosshead can safely absorb, said means including a pair of levers pivoted on said support adjacent one side of the machine and pivotally connected to said crosshead adjacent the opposite side of the machine, a third lever interposed between the levers forming said pair and pivoted on said support adjacent said opposite side of the machine and pivotally connected to said cross head adjacent said one side of the machine, and a pressure applying tool engageable by an intermediate portion of each of said levers and movable thereby toward the support to break the billets or other material.

10 6. In a machine for breaking billets or other materials the combination of a rigid machine frame, a crosshead movable relative to said rigid machine frame, said frame being capable of absorbing and said crosshead of delivering pressures up to a predetermined maximum without permanent deformation or rupture, and means interposed between said frame and crosshead and providing a support for billets or other materials to be broken and of developing pressures in excess of said predetermined maximum and sufficient to break the billets or other material without exceeding the predetermined maximum which the machine frame and crosshead can safely absorb, said means including a first lever pivoted on said support adjacent one side of the machine and pivotally connected to said crosshead adjacent the opposite side of the machine, a second lever pivoted on said support adjacent said opposite side of the machine and pivotally connected to said crosshead adjacent said one side of the machine, and a pressure applying tool engageable by an intermediate portion of said first and second levers and movable thereby to break the billets or other material.

15 7. In a machine for breaking billets or other materials the combination of a rigid machine frame, a crosshead movable relative to said rigid machine frame, said frame being capable of absorbing and said crosshead of delivering pressures up to a predetermined maximum without permanent deformation or rupture, and means interposed between said frame and crosshead and providing a support for billets or other materials to be broken and of developing pressures in excess of 20 said predetermined maximum and sufficient to break the billets or other material without exceeding the predetermined maximum which the machine frame and crosshead can safely absorb, said means including a pair of levers pivoted on said support adjacent one side of the machine and pivotally connected to said crosshead adjacent the opposite side of the machine, a third lever interposed between the levers forming said pair and pivoted on said support adjacent said opposite side of the machine and pivotally connected to said crosshead adjacent said one side of the machine, and a pressure applying tool engageable by an intermediate portion of each of said levers and movable thereby toward the support to break the billets or other material, said pressure applying tool being free of connection to said levers but urged into contact therewith by resilient means connecting said tool and support.
